*Isaac Adams of Boston Massachusetts
Lettres Patent*

*Wth Schedule referred to in these Letters Patent and making part of
the same containing a description in the words of the said Isaac
Adams himself of his improvement in the power printing press,*

*To all to whom these presents may come; Be it known that
I, Isaac Adams, Mechanist of Boston in the County of Suffolk
and State of Massachusetts, have invented a new and useful
improvement in the power printing Machine, and the following is
a full and true Specification thereof. Drawing No. 1, is an elevation
of the machine the front side of the frame being removed in order
to show the interior and operating parts. A A A A A is the opposite
side of the frame. B is a section of the bed, a a the form of
type. C is a section of the galley. D is a section of the in
fountain. E the fountain roller. C. is a composition feed roller
that conveys the ink from the fountain roller to the cylinder (B) upon
which it is distributed. E E are the rollers which distribute the
ink over the type. They are suspended in the slide frame (d, d, d)
in pairs in the usual way. e e are sections of two cross bars, which
connect the two side pieces of the slide frame together. This frame
is the carriage for the rollers, E E, and the nippes S, S, and the
fountain R R. It runs in grooved railways, No. 10, 10, 10, 10,
and motion is given to it in the following manner. f is a sec
tion of a vertical shaft which rests in bearings, on the sides of the
frame, and has an arm or lever at each end at, g g g. These
arms are connected to the sliding frame by means of pitman;
(h h), in the manner shown at h h i. (I) is another vertical shaft
on which is what I have named an alternator. k k k is the arm
(I) it also proceeds from this shaft and motion is communicated to
it and the alternator from the frame on, by means of the pitman
s, s, s. The alternator moves the arms, and consequently the slide
frame, by means of a roller which projects from the inner side.*

*2nd June 1846
Isaac Adams*

J. A.

of the sun on the rear end of the shaft of, into a crooked opening crooked
wise in the upper part of the alternator. As the machine is now ad-
vanced the roller last named would be in the upper part of the opening
in the alternator, now it is quite evident that when the alternator
begins to move, the roller together with the arms (y) and all at-
tached to them will be moved by it, and the roller will descend
in the opening until it arrives at O, where the opening begins
to be on a circle with the shaft (J). At this moment the side frame
will have arrived at the place where it must rest until the im-
pression is given. The alternator however continues to move on,
but the remaining part of the opening being on a circle with the shaft
it merely keeps the roller and all attached to it from moving
which the impression is being given. A completion of the roulette
of the cranks are, will of course bring the alternator, and conse-
quently the carriage or side frame back to where they now are.
This, by the means of the cranks are, and the alternator to the
necessary reciprocating, periodical movement, is obtained for the press
above described. G. G. is a stationary support upon which the shafts
to be printed are to be laid and printed. The support is hung on
pivots at q, to two standards, one rising from each side of the
frame. After a sheet has been printed it is taken from the type
pan, and carried in between the bed and the platen by nippers
on the rod s, which extends across from one side to the other of
the side frame. S, S, S, S, t, is a section of the two parts of the nippers
as, they appear when open at the moment before they close to set
the sheet. The two parts (S S S S) of the nippers are made of thin
plates of brass, plates of steel about four inches wide and are fastened
to other pieces of steel on the rod s, which are fastened together in the
manner of the joint of a hinge on the pin that holds it together
on the pieces that the under top of the nippers are fastened to are
projections (t) forming a sort of catch. The nippers are con-
tinually drawn together by means of spiral springs, around around the
rod s, one end of each being attached to the rod and the other

to the under half of the nippes. At one end of the rod is a piece projecting at a right angle, from it, about two and a half inches long on the outside of this projection, near to it and in, is a small roller which runs in a groove formed on the side of the frame for the purpose of operating the nippes. The manner of their operation is, as follows. Suppose the machine to be in motion and the nippes, (after an impression has been given) to be just emerging from under the platen. At this moment the roller on the end of the rod is entering the before named groove, which being arrested forces the roller downward, and causes the rod to turn. Now the upper half of the nippes, being so fixed to the rod that they cannot turn on it, will be elevated as they are raised towards the tympanum, high enough to be sure to come in over the edge of the sheet of paper as it lays on the tympan. When they get near to the tympan they are made to descend by an opportunity to bend or crook in the groove above named until they come down hard on the platen and the edge of the tympan which secures the sheet from moving from its place until the under half of the nippes are brought up, and owing thereto will at this moment have struck against projections on the frame and stopped but the slide frame continues to move on until the rollers are disengaged which allowing the under part of the nippes to be drawn up by the spiral springs against the upper parts. Then the sheet is seized by the nippes. H. L. is one of the two small cylinders, one of which is staved by a pin through its end to each side of the slide frame within these cylinders are spiral springs, and in their ends, are pistons, or slides, (L) which are kept out by the springs. They enter the slots on which the rod is placed and press it firmly against the opposite parts, so when the rod is stopped by the projection as above named the pistons will be pressed into the cylinders and when the slide frame moves back the rod will be forced back into its place by the expansion of the springs, when it is necessary to take out the rod and nippes.

piece, the slides, &c,) may be drawn back by pressing against the sheath & which project from them. The cylinder may then be raised and the rod and nippers removed. W is a section of a bar that is hung in the slide frame & projects at an angle of 45° to prevent the under part of the nippers from rising up when the upper part down. . . . Now the sheet having been seized by the nippers, as described above. The fingers are made to drop below the surface of the lymphase. . . . and the slide frame begins to move towards the platter in order to carry the sheet on over the top, as it moves along the before-named groove, operates on the roller on the end of the rod & and causes the nippers gradually to descend until they come to a horizontal position, at which position they are brought about the time they enter under the edge of the platter. The sheet as it is drawn from the lymphase falls on to the fingers. 1, 2, 3, 4, are rollers which extend from side to side of the machine, and there are six or eight lesser bands (the number of these requisite depends on the size of the fingers) that run on and connect the rollers 1, 2, 3, and also eight more bands which connect to the rollers 2, 3, 4 and on to pulleys on the shaft 5. These are all carried by means of a band from a pulley (I) on the fly-wheel shaft. J J is a section of a fly frame, constructed in the manner shown in the drawing. At Q. The fingers, 1 1 1 1 1 1 1 1 1 1 are covered with thin cloth in pairs, except the two outer ones, and when they lay horizontally come between the bands and pulleys named above. This fly is hung to the front side of the machine by the shaft K K and is operated on the following manner viz m. in drawing No 2 is a small toothed wheel on the shaft K K, and m. is a rack on the end of a rod O, which goes into it this rack is connected at its further end to a lever O. O. (Drawing No 1,) by a sheet pivoted on the free end of the lever is a roller P, which is operated on by a cam on the side of the wheel K K. Now when the machine is in operation the cam operates the lever O O which moves the

A.C. (Drawing No 2) which by means of the toothed wheel on. I. turns the flywheel to a horizontal position as shown in the drawing when when it is held a short space of time until a quick turn or falling off in the comb leaves the lever (C.C.) free, upon which a spiral spring (P drawing No 2) on the shaft K.K. causes it to turn and carry the flywheel to the table that stands near by for the purpose of continued movement of the comb, will turn the fly back, and so on alternately. It is a section of a bellows which turns from side to side of the machine nearly but not quite, q.q. are two openings which extends the whole length of the bellows. The Bellows is opened as follows. N is a shaft sustained in bearings on the sides of the machine. O.C. is one of two levers or arms, which extends out from the shaft under the Bellows. P.P. is a lever on the same shaft with a roller at its end that is, operated on by the comb Q. This roller should now be in contact with the comb, but I have drawn it in its present position in order to allow the roller to be presented open. R is, another arm extending from the same shaft with the weight (S) suspended from its end. when the machine is in operation the comb operates on the roller on the end of the lever P.P. and raises the weight S and throws down the arm O.C. which allows the bellows to open but when the highest part of the comb passes the roller the weight throws up the arms O.C. and closes the Bellows and forces the wind out through the opening q.q. The object of the Roller, Bellows, lever, Arms, and Bellows just described is to take the sheets of paper from the frisket after they have been printed, and lay them on a table prepared for the purpose, after a short time, in succession an impression of it is caused from under the platen on the frisket and paper along under the Tympan and Bellows I. At the moment the edge of the frisket has been raised as far as the roller S. the highest part of the comb Q will pass the roller on the lever P.P. which allows the weight S to operate the bellows and blow the air swiftly through the openings q.q. The current of air

thus obtained strikes the under side of the sheet and causes its edge up against the taper on the Rollers 1. 3. The Rollers and Taper being in motion, and the sheet also continuing to advance with the Fricket, the edge of the sheet is quickly brought between the roller 2. and the taper, on the Rollers 1. 3. The sheet thus seized continues to be carried along on the taper that runs over the Rollers 2. 4. and the pegs, on the shaft 5. until its edge strikes the upper edge of the main bar (6.) or back bone of the fly, which takes place about the time that the most prominent part of the cam on the wheel is passing the roller on the lever O. C. which allows the spiral spring on the shaft to be thrown the fly or and lay the sheet on the table above named. The Bed is raised and the impression given in the following manner. II' I' is an attenuator similar in principle to that described for giving motion to the fricke frame U U are the toggle joints, W. is a roller placed in a space for the purpose in the middle of the toggle joints, and on the pin in their centre joint. The attenuator is made to operate the toggle joints by means of the crank and pitman V V. Now suppose the machine to be situated as shown in the drawing. When it begins to move, the crank pin (m) on the cog wheel, will move in a downward direction. This by means of the two pitmans will carry the two attenuators forward & & will carry the arms p. g. along until the fricke is brought to the place where the impression must be given, but a little before the fricke has stopped the point y. on the attenuator I' I' will have come in contact with the Roller W. it may now be perceived that this part of the attenuator forms an inclined plane in the side of a lever of the second class X being the fulcrum and that as it continues to advance the Roller W. will roll upon the inclined plane until the attenuator has received a full motion in that direction at which time the toggle joints will have been forced up nearly to a perpendicular time which cause the type up firmly against the paper and platen and produce

the impression. A completion of a revolution of the wheel and cog wheel, will of course bring all the parts to a position they now are. $\S 8$ is a section of what I term the bottom base. it sustains the impression, and is connected to the platform by a two inch round bolt at each end. $\mathcal{Z}$ is a socket shaft suspended in bearings to the two sides of the machine, it has two arms extending from it to W. from the end of each of these arms arises a rod X and connects with the bed, on each of these arms is placed a spiral spring A A to assist in raising the bed. $\mathcal{Z}$ is one of two levers that the pin 10 passes through, to connect the toggle joints, to the bed. these levers are connected at H. to a bar 12 that rests on the spiral springs A A. 13.13. are sections of a wedge and screw, by means of which the impression is increased or diminished. The bed is kept steady in rising and falling by means of a guide, (14) at each end of the bed which runs in grooves on the inner sides of the frame, and also by the two rods X which keep it from running sideways. The ink is distributed in the usual way viz by rolling together the roller, and cylinder. The cylinder is carried by a band from a pulley on the fly wheel shaft to a pulley (16) on the shaft of the cylinder B. If. is a short roller which obstructs the ink laterally in the cylinder, it is connected to a small frame carriage 18.18. which runs in rods 19.19. it is made to travel by being placed obliquely against the cylinder. $\mathcal{C}$. 20 is a weight and lever connected to the short spindle 21. This spindle has a crook piece on its end from one end of which arises the rod (22) and connects with the little frame C. B. which the roller runs in. This last named frame is connected to the carriage (18.18) by a spindle. Now when the roller has arrived at one end of the cylinder a projection from the lower part of the roller which obstructs the rods 19.19. comes in contact with the lever 20/ and the roller continuing to advance turns it in the opposite direction. this by means of the little connecting rod

(2.2) occurs the obliquity of the Roller which causes it to communicate, passing the other way, and so on alternately. The fountain is constructed in the usual way excepting that the quantity of ink is regulated by means of a rod that runs the whole length of the fountain, and is made wedging at each end, the pieces which forms the bearings for the fountain Roller, bear against those parts of the Rods which are wedging, so that moving the Rod one way or the other enlarges or lessens the space between the Roller and scraper, for the ink to pass through. The rod is moved by means of a screw which screws into a little stud on the rod, and is attached to a similar stud on the fountain. Another way I have is to use a round rod made constrict at each end where they are forming the bearings of the fountain Roller come against it. This rod is placed in firm bearings on the sides of the fountain, and holes are made through one end of it so that by means of a small lever it may move on its axis, which has the same effect as moving the edge endwise. The pivots or guides of the Rollers, which distribute the ink over the type are put into smooth holes in the ends of the Rollers, and are kept out by means of springs, put inside of the Rollers. The object of this is that the guides, may be forced into the body of the Roller, and consequently be drawn out of the holes, that form their bearings so that the rollers may be handly removed from their places without having mortise copy over their bearings; another way to construct the rollers is, several figures, 14.2. drawing No 2. a. a. a. Fig 1 is a frame suspended to the first frame by the pivots b. b. To this is fixed another frame c. c. d. the ends c. c. of which are fitted in grooves in the ends of the frame a. a. a. The frame c. c. d. is kept out in its present place by a spring e. e. Fig 2. is a section of the frames above named, it is made with the nippes f. The nippes are secured to the side (d. Fig 1.) of the frame c. c. d. by means of tressels g. Fig 2. The nippes are closed by means of the Rod h. in the following manner. The Rod is secured to the frame d. by means of pins or screws (k) which pass through holes made in a diagonal direction through it, and its end i. is fastened to the end j. of the frame a. a. a. in the manner of a nail.

Now first before the upper parts of the nippes are brought on the edge of the sheet of paper and lymphau as described of the nippes before named. the lower part of the frame card is brought against projections on the sides of the machine which stopards, but the lower frame card continues to move, consequently its end piece at it is made to operate in the manner of a wedge against the end of the Rod to which stops along on the frame card, and the slot, being diagonal as above named sides up also, and close the nippes on the sheet. When the sheet has been raised nearly to the place where it is to receive the impression as above described, the end of the Rod to which is brought against an inclined plane which forces it back and leaves the nippes free to open again. A is a roller on the frame card by means of which the nippes are operated in the manner described of the first named nippes.

The lymphau is a frame of wood covered with cloth over on its upper side as far down as 245-25. 4. 26. are two small holes made in the end piece, at the further end of the lymphau, these are for the purpose of raising the end of the Rod, which it is necessary to pull across from end to end of the lymphau. when the paper is broad in order to keep its edge from bending down. The end of the rod is kept in its place by passing a pin through the end piece of the lymphau into a hole drilled for that purpose in the end of the Rod. The pin is made so as to be easily drawn out with the fingers, so that the rod may be quickly shifted from one place to the other. The pieces on the lymphau that are colored yellow in the drawing are secured in their places by means of the little bolts and nuts, D. 28. D. 29. 30. Points 31. 31. are pull through little projections, on their ends and are caused to project beyond the face of the lymphau... and to fall back (as to allow the sheet to be drawn off) by means of the little levers 32. 32. The ends of these levers come together and are attached to the end of another lever 33. 33. at the centre of the lymphau 34. This last named lever runs diagonally from the centre of the lymphau about eleven or eight inches it then turns and runs in a direction opposite of the machine until it reaches the further part of the lymphau. It then turns at right

angle, in the direction 33. 33. it is operated as follows. On the slide frame is a little comb, so situated that when the slide frame moves, along the comb comes under the end of the lever and raises it up, which thrusts the points out as they are shown in the drawing, and on the side of the machine is, fixed a spring, that will when the end of the lever is, raised as, above named, spring out under it and hold it up. Now when the time comes, for the points to be drawn in, another little comb on the side of the slide frame pushes off the spring and disengages the lever, which will then by its own weight drop down, and draw in the points. It is, sometimes necessary that the points should be placed so as to hang with each other lengthwise of the sheet and sometimes crosswise. It is, therefore necessary that the points should be so fixed, that their situation may be easily changed, for this purpose there are two circular holes, cut in the face of the tympanum, the common centre of which is, the steel or pin which connects the two levers that operate the points to the end of the lever 33. 33. The bolts 37. 39. are put through these slots, so that by loosening the nuts, on them the points, to which the points are attached may be moved round and secured at any point that may be required. The upper half of the nippors, are a little longer than the lower half, so that their ends may reach on to the edge of the tympanum (or the rod before named to confine the sheet before the under half fly up. There must be a number of pairs of nippors, of nippors, of different lengths, on account of the points, of being of various widths. 35. & 36. are sections of the two parts of the parchment tympanum frame, this is secured by two slide bolts, in the platter near 36. — 37. 38 are rollers to which a tympanum sheet is, secured. A long sheet is, prepared for this purpose (it may be made by pasting common sheets together) and rolled up on one of the rollers. Its end is then passed under the platter, and secured to the other roller, which is turned until the sheet is, drawn smooth under the face of the platter. Both rollers are then drawn from running by platters, being dropped into a salient ^{edge} sheet on the end of each roller. The ends of the sheet are secured to the rollers by

pulling them into grooves, along the sides of the rollers, and then passing a rod into the grooves on the paper. One or both of these rollers should be hung on springs, so as to continually draw, on the paper to take up whatever it may shrink. Now it is plain that when one place on the sheet, has been soiled by turning the rollers, a clean place may be drawn instead of it. The fountain roller is turned in the usual way by means of a fall and a toothed wheel. The fall is attached to one of the towers (39) which sustains the feed roller (C). H1. is the table upon which the stamp of paper to be printed is placed. H2. is the fly wheel. H3. H4. are rollers which sustain the platen, these rest on railways, formed by the top edges of the frames. When a form is to be put on to the bed the lymph and the frame and rollers, 1. 2. 3. H. are turned up and fastened by a knot; the platen may then be moved off from over the bed. The front roller nippes taken out, and the form put on in the usual way. H5. H6. is a slide attached to the side of the alternator, for the purpose of raising the platen so that the pin A6. may go into the aperture H7. in order to prevent any impression. This is effected by a lever one end of which is placed under the curved part (H8) of the slide, and the other end in a convenient place for the person who prints to put the foot on when an impression is to be made. The lever to which the feed roller is suspended are operated by means of projections on the guides, (H1) of the bed. The cylinder for the distribution of water may be made of wood or metal. The best way I think is to make it of metal, and make it hollow and light so as to be capable of holding water or steam. Then through a hole in the end (that may be stopped with a cock, a plug or valve) there may be hot water introduced in cold weather, or cold in warm hot weather, in order to regulate the temperature of the ink and rollers, or there may be a hole in the shaft of the cylinder and a pipe adapted to it through which steam may be introduced for the same purpose. An economical way of drying the paper after it has been printed on the second side is

to connect a drying cylinder to the end of the machine at which the paper is taken off. Drying cylinders are constructed in a similar or a similar manner to the metallic cylinder above described for the distribution of the ink, only they are made considerably larger and have a cloth (made into a band by sewing it round together) which runs on rollers, and against the sides of the cylinder so that the paper may enter between the cylinder and cloth band on one side, and come out dried at the other. The cylinder, being continually heated by means of steam, or water as above named or otherwise. In order to dry the paper as it comes from the press with an apparatus of this sort, the fly frame for throwing off the paper may be removed, and the cylinder and cloth band placed so near to the rollers on the shaft 3. that as the sheets are carried along over the rollers 3, 4, and the tape bands as above described they will be carried on the cloth band and be carried between it and the cylinder and be brought out at the opposite side dried, where they may be taken and disposed of by a person for the purpose. The grooves on the sides of the machine described above for the operation of the nips may instead of being made stationary be made in the end of a lever attached to the side of the frame, which may be operated by a ramb on the fly wheel of this, I believe to be the best way when accurate regulation is required, by it the upper parts of the nips may be brought down on the sheet after the nips has stopped, in this way the sheet is less liable to be displaced before it is fastened on by the nips. I claim the combination with printing presses, of the apparatus above described for pulling on, drawing and changing the type sheet. I claim the combination with printing presses, of the apparatus above described for fastening on, drawing and changing the type sheet. I claim the combination with printing presses, of the apparatus above described for taking the paper from the type sheet. I claim the combination of nips for seizing holding and drawing the paper into the press, with printing presses on which vibrating arms, or levers are used to move the rollers over the type, or to move the first or to move the

I claim the combination of the surfaces with the slide frame instead of with the friskets. I claim the combination above described of these parts, which are essential to the perfect operation of the nippes. I claim the combination of nippes for drawing the paper into the press, as above described with printing presses in which the ink is distributed ^{on} the rollers, that distribute it over the types, by means of cylinders or rollers instead of tables or plane surfaces. I claim the combination of wedges and also of eccentricity with the ink fountain for altering the space between the roller and the paper. I claim the combination above described of those parts which constitute the stationary type and the various parts connected with it, which are essential to the operation of the press and to facilitate the taking of the sheet by the nippes. I claim the combination of vibrating arms, or levers, for moving the rollers over the forme, for moving the frisket, or for moving both rollers and frisket, with printing presses in which a crant is used to operate the toggle joints which produce the impression. I claim the combination of stationary points (that is, points which never come between the bed and platen) with printing presses which vibrating arms, or levers, which move vertically are used for moving the rollers that pass over the types, for moving the frisket or for moving them both. I claim the combination of a crant which moves vertically to operate the toggle joints which produce the impression with printing presses, in which the rollers are placed between the bed and platen to ink the types. I claim the combination of the wedge for altering the impression with the bed instead of the bottom bar. I claim in apparatuses of various kinds may be used for raising the sheet from the frisket as above described, as, for instance, the balloon, the air pump, or the air-bag or revolving fan, and these may be used to raise the sheet by drawing air into holes just over the sheet of paper, or they be used as above described to raise the sheet up by pressing, producing a current of air against the under side. I claim the combination of the pneumatic apparatus, with printing presses, for raising the sheet of paper from the frisket. I claim the combination of rollers, as above described, and bands, and lucifers with printing presses, for removing the sheet from the frisket. I claim the combination of the fly frame with the rollers and with the

182.

pulling, and with the bands, as above specified for the purpose of carrying the sheets after they have received an impression to a table, or otherwise in use. I claim the mode or manner of connecting the tympan and the front, connected with the points for the more easily changing the points and getting Register. I claim the combination of ink rollers which have moveable quiet, long, and offings as described above with printing presses. The rollers referred to in this claim are those that distribute the ink over the type. I claim the combination of drying cylinders, with printing presses, for the purpose of drying the paper after it has been printed as, above set forth. I claim the combination of metallic distributing cylinders as above named with printing presses. This last claim is confined exclusively to the cylinders which transmit the ink to the rollers that pass over the type and also distribute it over them. I will also claim that this claim does not refer to fountain rollers. There may be two small cylinders instead of ^{the} one marked B in drawing No. 1. The claim last above will cover ^{the} presses, is, not to extend to cylinder printing machines. The above is a true specification of my invention, ^{and} as left. I have made some mistakes or forgot something.,
